UNITED STATES PATENT OFFICE.

WILFRED LEWIS, OF PHILADELPHIA, PENNSYLVANIA.

COUNTERBALANCE.

No. 841,161.

Specification of Letters Patent.

Patented Jan. 15, 1907.

Application filed September 20, 1904. Serial No. 225,278.

To all whom it may concern:

Be it known that I, WILFRED LEWIS, a citizen of the United States, and a resident of Philadelphia, in the county of Philadelphia and State of Pennsylvania, have invented a certain new and useful Improvement in Counterbalances, of which the following is a specification.

This invention relates to a counterbalance that may be used in many or all classes of machinery, and especially in those classes of machinery wherein the weight or bulk of an ordinary counterbalance is objectionable.

The most common form of counterbalance is the weighted lever; but this form is not practicable in all cases, and various arrangements of springs have been resorted to in order to counteract the effect of a weight or force acting in any given direction. Such spring-counterbalances, however, are objectionable in that the resistance offered thereby is variable and increases with the compression or expansion of the spring, and they for that reason are merely approximate counterbalances.

The primary object of this invention is to avoid the defects of and the objections to previous counterbalances and to provide by means of springs a uniform force acting in any given direction to counteract a uniform force or weight acting in the opposite direction.

Another object is so to adjust the springs that they may be used to exert more or less force, as may be desired, at the beginning or the end of the travel through which they are intended to act, and other objects, as will hereinafter appear.

To the ends thereof the invention consists of features of construction, arrangements, and combinations of devices hereinafter described, and more particularly pointed out in the appended claims.

Several embodiments of the invention are illustrated in the accompanying drawings, forming part hereof, in which—

Figure 1 is a vertical sectional view of an apparatus in which the invention is embodied. Fig. 2 is a like view of a modified arrangement. Fig. 3 is a diagram illustrating the principle of the invention. Fig. 4 is a plan, partly in section, on the plane indicated in Fig. 5 by the line 4-4 of another modification. Fig. 5 is an end view of the last-mentioned modification. Fig. 6 is a vertical sectional view on the plane indicated

in Fig. 5 by the line 6-6. Fig. 7 is a side elevation, and Fig. 8 is a vertical sectional view on the plane indicated in Fig. 5 by the line 8-8.

Referring to the drawings, the reference-numeral 1 marks a frame which is attached to the guides or standards 2, and it is remarked that these guides 2 may form part of the framework of the machine in which the counterbalance is to be used.

The reference 3 denotes a cross-head which is slidable along the guides 2 and is provided with a platform, carrier, or table *t*, on which may rest or to which may be secured the weight, load, or part which is to be counterbalanced, and 9 marks helical springs surrounding the guides or standards 2. The springs may be designed very accurately for the duty to be performed, or their tension may be varied, if desired, in any known or suitable manner.

The cross-head 3 and the carrier *t* in the instance shown in Figs. 1 and 2 are moved downward against the resistance of said springs 9 by means of a lever comprising an operating-arm 6, a shaft 4, to which the arm 6 is fast and which shaft is journaled in a lug depending from the frame 1, an arm 5, fast on said shaft 4, a crank-pin or wrist 7 on the said arm 5, and a rod 8, which rests and slides in bearings on the cross-head 3 and with which the crank-pin 7 is pivotally connected directly in the construction shown in Fig. 1 and indirectly in the construction shown in Fig. 2. A helical spring 10, surrounding the rod 8 and abutting against a part of the cross-head 3 and against a collar 26 on the rod 8, tends to move the rod and the pin 7 transversely of the apparatus. The parts are by preference so proportioned and arranged that the crank-arm 5 stands vertical, or nearly so, when the cross-head is in its upper position against the stops or frame 1, since this arrangement prevents any downward motion of the table *t*, as the same is loaded or weighted, until the lever 6 is operated.

As the lever 6 is swung upward and to the left in Fig. 1 the cross-head and the parts or weight supported thereby are moved downward against the resistance of the springs 9 and 10 until the time the crank-pin 7 reaches the horizontal through the axis of the shaft 4. Thereafter the spring 10 acts to move the table or carrier downwardly. With the springs 9 arranged to counterbalance exactly the weight or load when the crank 7 is on said line of centers the carrier will be held

in that position, the spring 10 exerting no moment either way—that is to say, the spring-rod 8 opposes and then assists the continued motion of the cross-head 3, according 5 to the positions of the crank 7 with relation to the horizontal, through the center of the shaft 4.

In the arrangement shown in Fig. 2 the crank-pin 7 acts indirectly through the link 11 upon the spring 10, which spring performs the same duty as the spring 10 shown in Fig. 1. The link 11 connects the crank-pin 7 to the cross-head 3, and the spring-rod 8^x is pivotally connected at 12 to the link 11. Fig. 15 represents an ideal construction capable of producing a perfect counterbalance, while Fig. 2 represents a more practical construction in which absolute perfection is sacrificed to convenience. In both cases, however, the 20 operation is substantially the same, and in Fig. 2 it is only the angularity of the link 11 that vitiates the result. The principle of the invention is perfectly embodied in the construction illustrated in Fig. 1, and to this 25 construction the explanatory diagram Fig. 3 will be seen to apply.

Referring to Fig. 3, the reference-letter C denotes the crank-shaft; P and P', the crank-pin in intermediate positions. Now it will 30 be seen as the crank-pin moves in the circle A P P' that the springs 9 will be compressed, for any point P at the angle α to the vertical line A B, by an amount represented by C P vers. α , represented on the diagram by the 35 distance O P. At the same time the spring 10 will be compressed by an amount represented by P M or C P sin. α . If both springs 40 9 and 10 are fully extended when the crank-pin is at the point A and begin to be compressed as the crank-pin moves through the angle α , then A M equal to P O represents the compression of the springs 9, and A O equal to P M represents the compression of the 45 spring 10. When the crank-pin reaches the point D in a line normal to the line A B at the center of motion of the crank-pin, both 50 springs will have the same compression, A C or C P, equal to the radius of the crank, and in this position the elastic force of each 55 spring should be equal to the weight of the cross-head 3 and the parts or load supported thereby or acting thereon. When this is the case, the cross-head will be in perfect equilibrium in any position for a part turn of the 60 crank, as a reference to Fig. 3 will easily demonstrate. In this mid-position—the crank-pin at the point D—the spring 10 has no effect, and the spring system 9 exactly 65 counteracts the weight. At any intermediate position P the spring 10 exerts a force represented by P M, and this force acting at the distance M C above the center C produces the moment P M x M C, and this moment is counteracted by the equal and opposite moment represented by the force M C

acting at the distance P M or N C, or P N at the distance P M. The sum of the forces P N and P O equals N O or C P, the radius of the crank, and this is true for any position whatever. For example, when the crank-pin moves to the position P' the spring 9 exerts the upward force P' O and the spring 10 the downward force P' N. The algebraic sum of these forces is N O, as in the previous position P. Friction aside, the counterbalance is therefore a perfect one and can be made to take the place of a weighted lever. In the construction shown in Fig. 2 the perfection of the counterbalance is to a slight extent affected by the angularity of the link 11; 80 but as the length of this link is increased the discrepancy diminishes.

It will be noted in the constructions illustrated in Figs. 1 and 2 that the cross-head 3 is brought to bear against the frame 1 when 85 the crank-pin 7 is a little off the line of centers, in which case it may be desirable to have the cross-head excessively counterweighted in order to hold it firmly against the frame 1. This can be effected easily by giving the 90 spring 10 a longer compression than is represented by the radius of the crank. For example, in Fig. 3 the vertical line A' B' may represent the base from which compressions of the spring 10 are to be measured. A little 95 excess of compression when the crank-pin is near the line of centers adds very much to the supporting power of the device; but adds very little to the effort required on the hand-lever 6 to overcome it. The arrangement, 100 therefore, is very flexible in its application. The cross-head 3 can be made to stay up or to stay down, according to the stiffness or adjustment of the springs 9 and 10. In Fig. 2 the spring 10 acts on the link 11, and it is 105 always the effect of this spring at the point 7 that is to be considered. If the point of connection between the spring-rod 8 and the link 11 be made adjustable lengthwise of the link, 110 the effective strength of the spring-rod may be varied or adjusted. It is obvious that the construction and operation of the springs 9 and 10 may be varied from that shown in 115 Figs. 1 and 2 without departing from this invention. For example, the springs 9 might act upon the crank 5 to produce the same effect as they do by direct action against the cross-head 3 or another crank-shaft, and another set of springs might be added to assist the crank-shaft and springs shown in Figs. 1 and 2.

When the table *t* is too large to be easily squared by the cross-head 3 and guides 2, a pair of shafts with cranks and links connected to four squaring-points may be advantageously employed, as shown in Figs. 4 to 8, inclusive. In this arrangement the frame 1^x is fixed to standards or guides 2^x near their bottom, and the carrier or table *t* is connected with rock-shafts 4^x, journaled on 120 125 130

the frame 1^x by the cranks 5^x and links 11^x , and the table or carrier t slides on the guides 2^x . The shafts 4^x are compelled to move together in unison by any suitable means, as by 5 geared segments or by the means shown in the drawings and next to be described. Each shaft 4^x has two pulleys or disks 14 15 fast thereto to turn therewith, and said disks 14 15 are connected in pairs by straps or ribbons 16 , which connect opposite sides of the disks 14 15 , so that one or the other of said straps or ribbons 16 is under tension during the operation of the shafts 4^x . This arrangement of ribbons is preferred to toothed gearing on 10 account of its compactness and adaptability to varying center distances. The cranks 5^x are thereby moved in reverse directions and the side thrust of the links 11^x is balanced one by the other. The ends of the straps 16 are clamped between blocks 17 and the disks 14 15 , said blocks being set into the disks and held in place by screws 18 . The disks 14 are splined or otherwise attached to the shafts 4 , while the disks 15 are adjustably connected 15 with said shafts 4^x , preferably as follows: The disks 14 have lugs or pins 19 on their sides next to the disks 15 , and the disks 15 have swiveled pins 20 thereon next to the disks 14 . Screws 21 pass through the lugs 19 and engage with threaded holes in the pins 20 , the preferred arrangement being such that each screw pulls or is under tension and not compression in tightening the straps 16 , as this avoids a swivel connection between 20 the screws 21 and the lugs 19 . 22 is a stop-arm fast on a shaft 4 and which coacts with the frame 1^x to limit the motion of the table t toward the frame 1^x , while one of the shafts 4^x has an arm or lever 6^x whereby it may be 25 operated, and the other shaft 4^x has an extension 23 thereon for arresting the arm or lever 6^x , as the links 11^x and the cranks 5^x are in line with each other or are a little past or short of the lines of centers. At one side 30 of the apparatus the cranks 5^x are extended at 24 beyond the shafts 4^x , and wrists 25 on the arms 24 are connected by a compression-spring 10^x and telescoping rods $8'$, which are pivotally connected to the cranks 25 and 35 which have disk-abutments 26 thereon for the spring 10^x . At the other side of the apparatus the cranks 5^x are extended at right angles at 27 28 to form bell-levers, and the arms 27 28 are arranged to have detachable 40 crank-pins 29 connected thereto, as by screw-threading the pins and holes in the cranks. The pins 29 have reduced ends on which cross arms or bars 31 are pivoted, the bars being held in place by washers and pins 33 . The 45 ends of the arms 31 are perforated, and the ends of a coiled spring $9'$ engage with the said perforations. The tension of the spring 9 may be varied by engaging one end thereof more or less with the corresponding cross- 50 arm 31 before engaging the other end thereof

with the other cross-arm 31 . It is remarked also that the tension of the springs $9'$ and 10 may be made adjustable, if desired, and that the crank-pins 25 and 27 may be set in adjustable cranks to control the effective stiffness 70 of these springs. With the parts arranged as shown in Figs. 4 to 8, inclusive, the springs counterbalance the table or carrier t and a given weight or load thereon, so that the operation of moving the lever 6 until the stop 22 strikes the frame 1^x and back until the lever 6^x is arrested by the stop 23 requires a minimum of effort. It will be seen that the springs $9'$ and 10^x as thus arranged on cranks at right angles are equivalent in effect to the 80 springs 9 and 10 shown in Figs. 1 and 2 and that the principle upon which all of the forms of the invention shown is based is illustrated in the diagram Fig. 3 of the drawings.

It sometimes happens that the carrier t is 85 to be loaded or weighted while the apparatus stands as in Fig. 4 and is to be moved when the apparatus has been inverted from that position. In such case the pins 29 are shifted to the arms 28 , the spring $9'$ being 90 connected with the said pins 29 , as above mentioned. Thus by shifting the crank-pins one hundred and eighty degrees the apparatus can be rolled over through the same angle, and the counterbalance becomes equally 95 effective in the new position.

The counterbalance herein shown has been used in practice in connection with mold-making machines.

The gist of the invention consists of two 100 springs or two spring systems acting at right angles to each other on a crank or cranks to support a given load in any position of that crank or cranks. Two parallel springs or spring systems on cranks at right angles to 105 each other are mechanically equivalent to the above, and the multiplication of springs and cranks to produce the same result comes within the spirit of my invention and the scope of my claims. I do not, therefore, 110 limit myself to the arrangements shown in the drawings and above described.

What I claim as new, and desire to secure by Letters Patent of the United States, is—

1. In a spring-counterbalance, a crank sustaining a load acting in a given direction, and a spring acting in the opposite direction, combined with a spring acting upon said crank normal to said direction, whereby the moments of the two springs acting to turn 120 the crank can be made exactly equal and opposite to the moment of the load upon the crank in all positions of the crank.

2. In a spring-counterbalance, the combination of a movable part, a plurality of 125 springs for moving said part, and means whereby certain of said springs first resist and then assist the progressive motion of said part in one direction while the remainder of said springs continually resist said motion. 130

3. In a spring-counterbalance, the combination of a guided carrier, a plurality of springs for moving said table or carrier, and means whereby certain of said springs first 5 resist and then assist the progressive motion of said carrier in one direction while the remainder of said springs continually resist said motion.
4. In a spring-counterbalance, the combination of a framework, a guided carrier, a 10 plurality of springs for moving the same, certain of said springs abutting against said carrier or a part connected thereto, and crank connection between certain of said springs 15 and the fixed framework.
5. In a spring-counterbalance, the combination of a framework, a carrier movable and guided thereon, a plurality of springs for moving said carrier, and crank connection 20 between certain of said springs and the said framework.
6. In a spring-counterbalance, the combination of a framework, a carrier movable thereon, a plurality of springs for moving said carrier, and crank connection between 25 certain of said springs and one of said framework and table elements.
7. In a spring-counterbalance, the combination of a framework, a part movable relatively thereto, a spring resistance for resist- 30
- ing progressive motion of said part in one direction, and crank-and-spring connection between said movable part and said framework.
8. In a spring-counterbalance, the combination of a framework, a carrier movable thereon, a spring resistance for resisting progressive motion of said carrier, a spring-rod on said carrier, and a crank on the fixed framework connected with said spring-rod. 35
9. In a spring-counterbalance, the combination of a framework, a carrier movable thereon, a spring resistance for resisting progressive motion of said carrier in one direction, a spring-rod on said carrier, and a crank 40 on which said rod is pivoted.
10. In a spring-counterbalance, crank mechanism for sustaining a load or uniform force acting in a given direction, combined with springs arranged some to act on said 45 crank mechanism or the load in the opposite direction, and the remainder to act upon said crank mechanism normal to said direction.

Signed at Philadelphia, in the county of Philadelphia and State of Pennsylvania, this 15th day of August, A. D. 1904.

WILFRED LEWIS.
